ILLUMINATED ADVERTISING DEVICE FOR
CASH REGISTERS

Royce Venting, London, England, assignor to Victor Advertisements Limited, Southend-on-Sea, England, a joint stock company of limited liability of England

Application December 16, 1937, Serial No. 180,120
In Great Britain January 9, 1937

2 Claims. (Cl. 40—132)

This invention is designed to provide electrically illuminated advertising devices or signs for cash registers of the well known type, such as at present in general use, having a reciprocatory 5 sliding cash drawer (arranged to be opened and closed for each cash transaction) and having a key or keys for operating cash recording mechanism which latter (a) indicates the amount of each transaction, and (b) shows the total amount 10 of a series of such transactions, the operation of the key or keys for each cash transaction serving to release the cash drawer.

According to the present invention a frame or casing made for example of metal adapted to carry or to have mounted therein or thereon a glass plate or plates or other transparent or translucent sheet or sheets carrying thereon the advertisement or advertisements or matter to be illuminated, are mounted and secured on the body 20 of the said cash register and advantageously mounted on and secured to the top of such cash register; and one or more electric lamps 25 or are mounted in electric lamp sockets provided to receive and hold said lamp or lamps in the interior of said frame or casing carrying the advertisements so that the advertisement or other matter to be illuminated is situated between said lamp or lamps and the observer or observers.

An advertising device or sign adapted to be 30 electrically illuminated, for use in conjunction with a cash register of the kind referred to, comprises, according to this invention, a casing or frame formed of rigid material, such for example as metal, adapted to be mounted on the exterior 35 of the cash register, said casing having a glass or other translucent plate or sheet or plates or sheets bearing the advertising matter to be displayed when illuminated, one or more electric lamp sockets on the inside of the casing for holding an electric lamp or lamps to illuminate 40 said advertising matter to be displayed, and a switch connected with said sockets and adapted to be attached to the cash register for operation by the drawer thereof in such a manner as 45 to be closed and thereby illuminate said advertising matter to be displayed only when the drawer is open.

Furthermore, an electric switch is provided 50 within or on the main casing of the cash register and arranged and mounted in such wise as to be operated (a) in one direction by a spring (to immediately close the lamp circuit) as the drawer is opened and (b) in the opposite direction by the inner end of the drawer (as the lat- 55

ter is being closed) to thereby break the lamp circuit.

Conveniently the switch is so positioned with relation to the drawer in the cash register that the path traversed by the switch arm for making and breaking the circuit is in the path traversed by the drawer. In such a construction reciprocal movement may be imparted to the switch arm by means of a rod carrying an abutment adapted to engage the end of the switch 10 arm, when the rod is moved longitudinally, for example, by pressure of the back end of the drawer against the end of the rod in opposition to a spring which restores the rod to its original position on release of pressure of the closed 15 drawer.

One particular construction in accordance with this invention will now be described with reference to the accompanying drawing in which:

Fig. 1 shows in perspective an electrically illuminated advertising device fixed on the top of a cash register partly shown in outline, together with the electrical connections to a plug and to a switch fixed to the inside of the casing of the cash register at the back of the drawer, a side view of the inner end of the drawer and the switch in position being included in outline.

Fig. 2 shows a method of connecting two electric lamps for illuminating the sign with a plug 30 on the one hand and a switch on the other.

Fig. 3 shows a front view of the cash register in broken outline with the illuminated sign in position.

Fig. 4 shows (on an enlarged scale) details of 35 the switch in section.

Fig. 5 shows a vertical cross section of the casing.

Referring now to the accompanying drawing:

The illuminated sign consists of a simple casing 40 10 with a translucent glass side 11 bearing an advertising device and containing inside electric lamps 12. The lamps 12 are connected to a wall plug through a switch 13 (Fig. 4) attached to a bracket 14 which is screwed on to a cover plate 45 15 fixed to the inside of the back of the casing of the cash register by means of another cover plate 16 on the outside of the casing and bolts 17. A rod 18 is supported horizontally by bearings 19 in the upright portion of the bracket 14 50 and the cover plates 15 and 16.

The illuminated sign consists of a casing 10 provided at its lower part with dependent flange 101 adapted to embrace the upper part of a cash register which is indicated in chain dotted lines 55

in Fig. 1. Within the casing 10 and adjacent to the ends thereof are plates 102 on which are mounted electric lamp sockets 121 each adapted to hold within the casing an electric incandescent filament lamp 12 with its axis generally horizontal. The lamp sockets 121 are wired in parallel and are connected to a wall plug through a switch 13 (Fig. 4) attached to a bracket 14 which is screwed on to a cover plate 15 fixed to the inside of the back of the casing of the cash register by means of another cover plate 16 on the outside of the casing and bolts 17. A rod 18 is supported horizontally by bearings 19 in the upright portion of the bracket 14 and the cover plates 15 and 16. The switch arm 21 in making and breaking moves reciprocally in a path perpendicularly below the axis of the rod 18. The outer end 23 of the switch arm is provided with a groove or hollow at right angles to the direction of movement of the switch arm 22, the depth of the groove or hollow being such that when the switch arm is in an upright position the bottom of the hollow roughly coincides with the end of the collar 20. The end of the rod 18 abutting on the end of the drawer is provided with a rubber buffer 24 fixed thereon by means of a screw 25 provided with lock nuts 26 to adjust the buffer to the required position. In operation, when the drawer of the cash register is pushed home to its closed position the end of the drawer bears against the buffer 24, pushes the rod 18 in a longitudinal direction which carries the collar 20 towards the cover plate 15 and compresses the spiral spring 21 against the cover plate 15. In its passage towards the cover plate 15 the collar 20 engages one side of the groove 23 in the end of the switch arm 22 and carries the switch arm over into the "off" position of the switch. When the drawer is opened, the release of the pressure on the buffer 24 enables the spring 21 to expand and push the collar 20 into engagement with the opposite side of the groove 23 of the switch arm 22, which latter is then moved over to the "on" position.

position of the switch where it will remain until the drawer is again closed and presses on the buffer 24, thereby moving the switch to the "off" position and holding it there until the drawer is again opened.

A device constructed in accordance with this invention is easily attachable to an existing cash register of the type referred to and requires no modification of the recording mechanism of the cash register. Alternatively the casing and switch may—while manufacturing cash registers of the type referred to—be incorporated in and form a part of such cash registers.

What I claim is:

1. For attachment to the top of a cash register, an electrically illuminable sign including a frame comprising a flanged plate in the form of an inverted U and constituting top and end walls of said frame and having the bottom part provided with a surrounding dependent flange adapted to embrace the top of the cash register for mounting the casing thereon, a pair of vertical supports arranged within the casing and parallel to and adjacent the end walls thereof, an electric lamp socket mounted on the inner face of each such support, and flat panels closing the open faces of said frame, at least one of said panels being of translucent material and bearing display matter.

2. For attachment to the top of a cash register, an electrically illuminable sign including a casing comprising a flanged plate in the form of an inverted U and constituting top and end walls of said casing and a bottom part provided with a surrounding dependent flange and adapted to embrace the top of the cash register for mounting the casing thereon, a pair of vertical supports arranged within the casing parallel to and adjacent the end walls thereof, an electric lamp socket mounted on the inner face of each such support and flat panels closing the open faces of said casing, at least one of said panels being of translucent material and bearing display matter.

ROYCE VENTING. 4
